UNITED STATES PATENT OFFICE.

THOMAS J. BALL, OF BOSTON, MASSACHUSETTS, ASSIGNOR TO UNITED SHOE MACHINERY COMPANY, OF PATERSON, NEW JERSEY, A CORPORATION OF NEW JERSEY.

MACHINE FOR PREPARING INSOLES.

1,179,494.

Specification of Letters Patent. Patented Apr. 18, 1916.

Application filed August 4, 1911. Serial No. 642,341.

To all whom it may concern:

Be it known that I, THOMAS J. BALL, of Boston, in the county of Suffolk and State of Massachusetts, have invented certain new and useful Improvements in Machines for Preparing Insoles, of which the following is a specification.

The present invention relates to machines used in the manufacture of boots and shoes and more particularly to machines for preparing for reinforcing what are known commercially as "Gem" insoles. The term reinforcing is used by those skilled in the art to designate the operation of forming a bead or crimp in the reinforcing material and securing it to the insole.

It is customary to apply a blank of reinforcing material to the channeled face of the insole before passing it through the reinforcing machine. The reinforcing material employed is usually canvas or duck suitably coated with an adhesive substance. Heretofore, the blank of reinforcing material has been applied to the insole in a width sufficient for the sole at its widest point, namely, the ball. The width of this blank has been equal at all points, the edges of the blank being straight and parallel, so that a relatively great quantity of material has had to be trimmed from the reinforced insole around its shank after the completion of the reinforcing operation. This manner of preparing an insole for reinforcing has been found to be very wasteful of the expensive reinforcing material.

The object of the present invention is to provide a machine for preparing insoles for reinforcing by which individual blanks of insole reinforcing material may be produced with a minimum waste of stock.

To the accomplishment of this object one feature of the invention contemplates the provision, in a machine for preparing insoles for reinforcing provided with means for feeding a sheet of reinforcing material, of means for cutting the sheet along lines having a predetermined relation to the lateral curvatures of an insole movable simultaneously with the sheet.

Broadly considered, the lines of cut may be intermittent or continuous and may bear any relation to the lateral curvatures of the

insole movable simultaneously with the sheet as found desirable or expedient.

In the preferred form of the invention the lines of cut are formed in the sheet parallel to the lateral curvatures of the insole and this feature is important as part of the invention. According to this feature of the invention a blank of reinforcing material is produced which has the necessary width opposite the ball of the sole and which has no more than the necessary width opposite the shank portion. The economic advantage of this feature is of considerable importance as the saving represents not only the cost of the fabric but the cost of the coating substance and the cost of applying it to the fabric.

Reinforcing material may be conveniently coated in sheets about fifty yards long and about thirty inches wide.

Accordingly, another feature of the present invention contemplates the provision, in a machine for preparing insoles for reinforcing, of means for feeding a sheet of reinforcing fabric, and means for dividing the sheet into strips along lines in accordance with the outline of a series of insoles movable simultaneously therewith.

Broadly considered, the insoles may be arranged to move simultaneously with the sheet during the feed of the latter in any suitable manner. As the insoles are to be consolidated with the blanks formed from the strips it is desirable to stick the insoles directly to the sheet and to control the cutting of the sheet into strips directly from the insoles carried thereby.

Preferably the soles are stuck to the sheet in rows, and the ball portion of each sole is arranged in the transverse line of the shank portion of an adjacent sole. When all the soles are arranged in this relation, providing a suitable space between the rows, a serpentine path is defined by the confronting edges of the soles. The soles are spaced so as to leave sufficient exposed sheet material to cover one side of each sole when the sheet material is contracted by being molded about the stitch-receiving ribs with which the soles are provided. The soles are laid so that their stitch-receiving ribs are toward the sheet material.

In order to prevent the sticky strips from crossing one another after the sheet is divided and thus become entangled, the invention contemplates the provision, in a machine for preparing insoles for reinforcing, of means for separating the divided strips to prevent their sticking together, in addition to means for feeding a sheet of reinforcing fabric, means for rendering the sheet adhesive and means for dividing the sheet into strips.

These and other features of the invention including certain details of construction and combination of parts will be further explained in the following description and then particularly pointed out in the appended claims.

Of the accompanying drawings which illustrate the best form of the invention at present devised—

Figure 1 represents a side elevation, partly in section, of a complete machine. Fig. 2 represents a top plan view thereof with soles arranged in rows on the sheet material. Fig. 3 represents, on a larger scale, a vertical section in a plane indicated in Fig. 2 by the line 3—3. Fig. 4 represents a top plan view of one of the devices in which a cutter is mounted. Fig. 5 represents a side elevation of a detached cutter. Fig. 6 represents a rear elevation of one of the cutting devices in operative position with relation to the work. Fig. 7 represents a horizontal section in the plane indicated in Fig. 3 by the line 7—7. Fig. 8 represents a vertical section of a locking device indicated in Fig. 1 by line 8—8. Fig. 9 represents a cross section of an insole.

The same reference characters indicate the same parts wherever they occur.

The machine for operating upon the sheet material comprises means for feeding the work edgewise with the soles stuck to the reinforcing material. The machine is provided with cutters whose function is to divide the sheet between the soles. Each cutter is supported by an independently movable member which is adapted to move transversely with relation to the feeding movement of the work. The members which support the cutters are adapted to be engaged by the lateral curvatures of two adjacent soles and to be moved from side to side by the said curvatures so as to cause the cutter to cut in a serpentine path between the soles. In this way the sheet material may be divided into strips whose outlines are determined by the outline and arrangement of the soles. After the material has been divided into strips in this manner it may be cut transversely to divide it into individual blanks. The insole is thus prepared for reinforcing.

The sheet material which the present machine is designed to prepare is indicated at

10. As shown by Fig. 1, the sheet material is wound in the form of a roll 11. One side of the material is coated with suitable substance 12 which under normal conditions is not sticky but which is adapted to be rendered sticky by the application of heat or a liquid solvent.

The roll 11 is mounted between two upright frame members 13 fastened together by suitable transverse tie members such as those indicated at 14. The members 13 are provided with brackets 15 adapted to support a spindle 16 extending through the center of the roll 11. The web of material 10 is drawn from the roll over a drum 17 and thence over a bed 18 in such manner that its coated side will be uppermost upon the bed. The insoles α are laid upon that stretch of the sheet material which is traversing the bed 18, and they are carried by the sheet material between two coactive rolls 19 and 20, thence between two coactive rolls 21 and 22, and thence to a delivery table such as that indicated at 23 at the left of Fig. 1. A tension device comprising a band 24 and one or more springs 25 is arranged to act upon the roll 11 to retard the rotation thereof.

The cutters hereinafter described are arranged to act upon the stretch of material between the rolls 20 and 21. The rolls 21 are driven to effect the feeding of the work, and the roll 26 is provided with a friction brake for the purpose of maintaining the desired degree of tension upon the work to prevent wrinkling in the stretch upon which the cutters act. The friction brake is shown by Fig. 3 and comprises a braking surface 26 on the roll, a band 27 engaging said surface, and a rod 28 and spring 29 for exerting tension upon the band. The roll 19 is preferably mounted so as to be movable away from the roll 20 in order to facilitate the insertion of the sheet material. For this reason the ends of the roll 19 are mounted in a pair of arms 30 which are adapted to swing from the position shown by solid lines in Fig. 1 to the position indicated by dotted lines in the same figure. The arms 30 are slotted for the reception of the ends of the roll, so that the roll may yield in accordance with the varying thickness of the work. The weight of the roll is sufficient to preserve the necessary tension. According to this embodiment of the invention, the drum 17 and bed 18 are heated for the purpose of rendering sticky the coating substance 12. The heating means illustrated comprises a gas pipe 31 extending through the center of the drum, and a gas pipe 32 extending under the bed 18. These pipes are provided with openings 33 which constitute burners.

As shown by Fig. 2, the machine is provided with two rolls 21 which are arranged

at an angle to each other. The upper rolls 22 are likewise arranged at an angle which corresponds to the angle of the rolls 21. The purpose in arranging the rolls in this manner is to adapt them to laterally spread the strips into which the sheet material has been divided, to avoid overlapping and consequent sticking of one strip to another. The rolls 22 are divided into a plurality of sections, and their central bore is considerably greater than the spindle 22' upon which they are mounted. The sections are therefore adapted to be displaced independently of each other as the thickness of the work varies and to keep the work in contact with the roll 21 with substantially equal pressure at all points, notwithstanding variations in the thickness. The rolls 21 are driven in order to effect the feeding of the work. The feeding means illustrated includes sprocket wheels 34—one on each roll 21—chains 35, and driving sprockets 36 affixed upon a shaft 37. The shaft is mounted in bearings in the frame members 13. A continuously driven shaft 38 is mounted so that one end may be movable toward and from the shaft 37. The movable bearing therefore is afforded by an arm 39 pivoted at 40. A gear 41 affixed to the shaft 38 is adapted to be moved into and out of engagement with a gear 42 affixed upon the shaft 37. The upper end of the arm 39 is provided with a latch 43 which cooperates with a notched sector 44 by which the gear 41 may be held out of engagement or in engagement with the gear 42. The drum 17 is provided with a sprocket wheel 45 which is connected by a chain 46 with a sprocket wheel 47 affixed to the shaft 38. The direction of rotation of the drum driven in this manner is opposite with relation to the direction in which the sheet material is fed. The drum therefore slips upon the sheet material and maintains suitable tension to keep the material taut between it and the roll 20. The feed rolls 21 are preferably covered with a jacket similar to the clothing of a card roll in order to insure feeding the sheet material notwithstanding the reverse tension exerted by the roll 20, drum 17 and friction band 24.

The several cutters are mounted in suitable holders which are supported by a transverse rod 48 arranged above the work between the rolls 19 and 22. The ends of the rod are supported by the free ends of the arms 30. The arms are provided with portions 50 adapted to rest upon upper surfaces of the frame members 13 when the arms are in operative position. The frame members are provided with latches 51 which are adapted to engage shoulders 52 on the extensions 50 to lock the arms in operative position. The latches are normally held in locking position by springs 53.

The form of cutter which at the present time seems to be best adapted to perform the operation of cutting the sheet material into serpentine strips is that shown by Fig. 5. The blade of the cutter is indicated at 70 54 and the cutting edge is indicated at 55. The outline of the cutting edge resembles the letter V. The blade is reduced to a sharp point at 56 which is adapted to penetrate the sheet material when the blade is moved to 75 operative position. The blade is formed with a slot 57 which is adapted to receive a pin affixed in a follower 58.

The follower is provided with a cylindric stem 59 which is mounted in bearings 60 in 80 a swinging arm 61. A collar 62 affixed on the stem 59 prevents endwise movement of the stem in its bearings. The follower is provided with projections such as pins 63 (see Fig. 7) for engaging a lip 64 formed 85 on the arm 61 to limit oscillatory movement of the follower with relation to the arm. The extreme positions of the follower are indicated by dotted lines in Fig. 7, and the normal median position is that shown by 90 solid lines. The opposite surfaces 65 of the follower are adapted to be engaged by the edges of the insoles in two adjacent rows. The follower is provided with lips 95 66 which extend laterally for the purpose hereinafter explained. The blade 54 is inserted in a longitudinal vertical groove 67 in the follower and is held in position by a pin 68 extending transversely through the follower and bridging the groove 67. When the blade 54 is inserted in the slot 57 and moved in the direction of feeding movement, the pin 68 enters the slot 57 until it occupies the relation shown by Fig. 5. The blade is thus rigidly secured in the follower. The follower is normally held in 100 its median position by a spring 69 which, as shown by Fig. 3, extends from the forward end of the follower to an eye on the arm 61.

The arm 61 is pivotally connected by a stud 70 with a bracket 71. The bracket is provided with an opening for the reception of the transverse rod 48 and is provided with a setscrew 72 adapted to engage the rod to fix the position of the bracket. The rod is preferably provided with a longitudinal groove 73 for the reception of the end of the setscrew, whereby the bracket may be positively locked against rotative movement about the rod. The rod is affixed in the arms 30 so that it is likewise locked against rotative movement. The arm 61 is provided with a roll 74 arranged to engage the under surface of a segmental arm 75 extending from the bracket 71. The function of the roll is to sustain the arm 61 against the stress imposed by the work, whereby the pivot stud 70 is relieved so that it will not bind in its bearing. 110 115 120 125 130

An insole of well known construction is shown in cross section by Fig. 9. The edge of the insole is slit around the forepart and along the shank so as to provide a feather 5 x' and a stitch-receiving rib x^2 , the rib being bent at right angles in the usual manner. In practice, the insoles are laid upon the sheet or web of material so that their ribs x^2 extend downwardly and engage the sticky 10 substance 12. The attendant will stand in the vicinity of the drum 17 and bed 18 and arrange the soles in rows as shown by Fig. 2. It will be observed that the heel of one sole overlaps the toe of the next sole in the same 15 row. The soles are overlapped in this manner because it is not necessary to cover the heel seats with the material 10. The soles are not only arranged in longitudinal rows but they are arranged in transverse rows, 20 and a sole in one transverse row is preferably arranged to extend in the opposite direction with relation to the adjacent soles in the same transverse row. The widest part of one sole is arranged in the transverse line 25 of the narrowest part of the adjacent sole and a suitable space is left between the soles so as to form serpentine paths extending longitudinally of the work. When a sufficient number of soles have been stuck to the 30 sheet or web of material the arm 39 is moved to connect the driving mechanism to effect the feeding of the work. If the cutters are not already in cutting position, intersecting the plane of the work, their points 56 will 35 readily penetrate the sheet material when the arms 30 are placed in operative position. The several brackets 71 by which the cutters are mounted upon the rod 48 are set at the appropriate positions, as determined by the 40 longitudinal rows of soles. Each follower 58 enters between the confronting edges of two soles in the relation shown by Fig. 6. The lips 66 are overlapped by the feathers x' and serve to prevent the work from receding. 45 The outer edges of the lips 66 are adapted to be engaged by the ribs x^2 , while the surfaces 65 are adapted to be engaged by the feathers x' . As the work progresses, the several followers are moved from side to 50 side by the sole and the cutters cut the work into strips along serpentine lines, as shown by Fig. 2, the lines of the cuts corresponding with more or less accuracy with the lines defined by the edges of the soles. The strips 55 become spread apart as the result of passing between the feed rolls and sectional rolls, and in this relation they are deposited upon the delivery table 23. The strips may be thereafter severed as desired in order to prepare the individual blanks for molding. 60

The machine is provided with guards adapted to be brought into use when the feeding operation is interrupted for a considerable length of time, for the purpose of preventing undue heating of the sheet ma- 65

terial. These guards are indicated at 76 and 77. The guard 76 is adapted to enter between the drum and the sheet material to disengage the material from the drum and to provide a suitable air space through 70 which the heat may escape. The function of the guard 77 is to bridge the gap between the top of the drum and the adjacent edge of the bed 18. The guard 76 is attached to a transverse rod 78 which connects two arms 75 79, one at each end of the drum. The arms are adapted to swing about the axis of the drum from the position shown at the upper side of the drum to the position shown at the lower side of the drum. The ends of the 80 rod 78 are preferably extended outside the arms in order to provide suitable handles by which the guard may be positioned. An angular portion 80 at one edge of the guard 76 is adapted to engage a crossbar 81 attached to the under side of the guard 77. When the guard 76 is moved in a clockwise direction it lifts the work away from the drum and finally draws the guard 77 across the gap previously indicated. When the 85 guard 77 is moved in the opposite direction, the arms 79 strike against the crossbar 81 and repel the guard 77 so as to open the gap between the drum and the bed.

The herein-described method of cutting 90 the reinforcing material makes it possible to use substantially all of a large sheet from which the strips or blanks are produced. It is found that this method will produce nine strips suitable for men's soles, or thirteen 100 strips suitable for children's soles, from a sheet which would yield only seven strips for men's soles or nine strips for children's soles if the width of the strips were uniform. This saving is very important, because the reinforcing material represents not only the cost of the fabric but the cost 105 of the coating substance and the cost of preparing the fabric.

Aside from the economical advantage of 110 the present method, there is another advantage. The manufacturers of insoles may produce by this improved method soles of all sizes from sheets of standard or uniform width. In other words, the size of the soles 115 which may be produced is not dependent upon the width of the reinforcing material at hand, but the production of soles by the former method is dependent upon the width of strips available for immediate use. 120

It is obvious to those skilled in the art that patterns instead of insoles may be employed to control the cutting of the sheet material into strips and so it is to be understood that the term insole as used throughout the claims means broadly any device having the lateral curvature or curvatures of an insole.

I claim:

1. A machine for preparing reinforcing 130

material for insoles having, in combination, means for supporting a web of reinforcing material having a series of insoles carried thereby, knife carriers mounted above the 5 web cutting knives secured in said carriers for dividing the web into strips, means for feeding the web, and guides on the carriers for engaging the insoles to move the knives laterally approximately in accordance with 10 the outline of major portions of the length of the margin of each insole on the web, substantially as described.

2. A machine for preparing reinforcing material for insoles having, in combination, 15 means for supporting a web of prepared reinforcing material having a series of insoles positioned thereon, means for rendering the web adhesive for attaching the insoles to the web, a knife for dividing the web into strips, 20 and a guide for contacting only the insoles to move the knife in accordance with the outline of marginal portions of the insoles on the web, substantially as described.

3. A machine for preparing reinforcing material for insoles having, in combination, 25 means for supporting and feeding a web of reinforcing material having a series of insoles attached thereto, a knife, and a guide connected therewith and mounted for unrestrained movement back and forth across the web, said guide being constructed to engage marginal portions of the insoles to govern the path of cut of the knife, substantially as described.

4. A machine for preparing reinforcing material for insoles having, in combination, a plurality of rotary members for supporting a web of reinforcing material having a series of insoles arranged in rows and attached thereto, a plurality of cutting knives for operating between the rows of insoles, guides on said knives constructed and arranged to be moved between the rows and held out of contact with the web, and means 45 for rotating said members to feed the web, substantially as described.

5. A machine for preparing reinforcing material for insoles having, in combination, means for supporting a web of reinforcing material having a plurality of rows of insoles attached thereto, a cutter for dividing the web, means for feeding the web, and a guide on said cutter constructed to contact the marginal portions of the insoles of two 50 adjacent rows to move the cutter laterally to make a cut substantially equi-distant between the rows, substantially as described.

6. A machine for stripping fabric for reinforced insoles having, in combination, 55 means for supporting a web of reinforcing material, a plurality of carriers mounted for reciprocatory movement across the web, a cutting knife having a swivel mounting in each of said carriers, the adjacent carriers 60 being arranged for movement alternately

toward and from one another to guide the knives in making a series of sinuous cuts, and means to feed the web against the knives, substantially as described.

7. A machine of the character described, a 70 fabric cutting blade, means for feeding a sheet of reinforcing fabric having a plurality of insoles stuck thereon and spaced apart side by side against said blade, a sole engaging member freely movable transverse to the 75 line of feed on which said blade is mounted, and means for supporting said sole engaging member so that it will be engaged by marginal portions of adjacent soles on opposite sides of the blade and thereby move 80 from side to side with relation to its supporting means in making a cut, substantially as described.

8. A machine of the character described, a 85 plurality of fabric cutting blades, means for feeding a sheet of reinforcing fabric having a plurality of rows of insoles stuck thereto against the blades, said blades being arranged to cut intermediate adjacent rows of insoles, a sole engaging member movable 90 across the line of feed for each blade, and means for supporting said sole engaging members so that they may be moved independently of each other from side to side by contacting marginal portions of their adjacent rows of insoles, substantially as described. 95

9. A machine for preparing reinforcing material for insoles, having, in combination, 100 means to support and feed a web of prepared reinforcing material having a plurality of rows of insoles positioned thereon, means to heat the reinforcing material to render it adhesive for attaching the insoles thereto, means to divide the sheet into strips, 105 and means constructed to engage the insoles to laterally separate the strips.

10. A machine for preparing insoles for reinforcing, having, in combination, a pair of rolls constructed to feed a sheet of sticky 110 reinforcing fabric, means for dividing the sheet into strips, and two pairs of spreading rolls arranged above and below the sheet and constructed to force the strips apart laterally to prevent their sticking together, 115 substantially as described.

11. A machine for preparing insoles, having, in combination, a pair of rolls for feeding a sheet of reinforcing fabric, means for dividing the sheet into strips, a pair of auxiliary spreading rolls arranged above and below said sheet for engaging the strips extending across substantially one half of the strips and arranged at such an angle to the path of feed as to force the strips engaged thereby apart laterally, and a second pair of auxiliary feed rolls correspondingly placed with relation to the remaining half of the strips, substantially as described. 120

12. A machine for preparing reinforcing 125

material for insoles, having, in combination, means for supporting a web of reinforcing material, a plurality of carriers mounted for unrestrained reciprocatory movement across the web, a cutting knife mounted in each carrier, the adjacent carriers being arranged for movement alternately toward and from one another to guide the knives in making a series of alternately diverging and

converging cuts, and means to feed the web 10 against the knives, substantially as described.

In testimony whereof I have affixed my signature, in presence of two witnesses.

THOMAS J. BALL.
